(57) **CLAIM**

The ornamental design for a heat sink for a lamp, as shown and described.

DESCRIPTION

- 1.1 is a perspective view;
- 1.2 is a front view;
- 1.3 is a back view;
- 1.4 is a top view;
- 1.5 is a bottom view;
- 1.6 is a left view and
- 1.7 is a right view.

The heat sink for a lamp is shown with symbolic breaks in its length. The appearance of any portion of the heat sink for a lamp between the break lines forms not part of the claimed design. In the reproductions, the broken lines are for the purpose of illustrating portions of the heat sink for a lamp that form no part of the claimed design.
